UNITED STATES PATENT OFFICE.

FLOYD L. STAFFORD, OF REPUBLIC, KANSAS.

OIL BURNER.

Application filed April 20, 1926. Serial No. 103,306.

The present invention relates to oil burners, and more particularly to a burner of the open retort type utilizing a natural draft.

An object of the present invention is to provide an oil burner capable of producing a blue flame when used on a high and on a low fire and which is of the open retort type utilizing natural draft and gravity feed, and a burner which produces practically no smoke or carbon, and one which requires no cleaning or other attention during its long continued use.

Another object of the invention is to provide a burner with means for so distributing a natural draft that but a small draft is required, and which consumes completely and thoroughly a relatively small amount of oil but which at the same time produces a relatively hot flame.

A further object of the invention is to provide a burner with an improved wick and spreader, the same comprising a wire encased in asbestos and supporting a layer of wood ashes, utilizing the principle of the oil adhering to and following metal more readily than ashes so as to first spread the oil and subsequently effect the absorption of the oil by the ashes to vaporize the ashes, particularly under the influence of heat for distribution to the draft of air directed over the upper surface level of the ashes.

A further feature of this invention is to provide means of draft for enveloping the inner and outer sides of the burner, particularly when the draft is high or at full force, to eliminate vibration and back pressure in the burner and automatically takes care of the draft under all weather conditions in supplying the proper amount of oxygen to produce the blue flame and a quiet flame which will not flicker.

The invention also aims to provide means to collect and drain off excess quantities of oil to prevent oil from overflowing the burner.

The invention also provides an improved draft ring to insure the proper admission of air to the burner even when the same is packed, particularly when the burner is installed in furnaces and the like.

The above and various other objects and advantages of this invention will in part be described in, and in part be understood from the following detailed description of the

present preferred embodiment, the same being illustrated in the accompanying drawing, wherein:

Fig. 1 is a vertical central section taken through an oil burner constructed according to the present invention, and

Fig. 2 is a horizontal section taken through the burner on the line 2—2 of Fig. 1.

Referring to the drawing, 10 designates a base plate of ring form having a central air opening 11 and which at its upper side is dished out to provide a generating cup 12 extending annularly in the base ring. The base ring 10 is supported at its outer edge portion upon the upper edge of a pan 13 which is provided with an outstanding flange 14 about its upper edge extending beyond the base ring 10. The pan 13 is thus relatively large and is adapted to catch the overflow from the burner, the inner marginal flange 15 of the base ring 10 being of less height than its outer flange or wall to permit of the overflow of the oil into the overflow pan 13. Arranged about the overflow pan 13 is a downwardly curved draft ring 16 secured at its upper edge to the flange 14 by bolts 17 or the like. This draft ring 16 at its lower edge stands outwardly about the pan 13 and provides a free air passage about the pan, the air entering the pan through relatively large draft openings 18 formed in the annular wall of the pan.

Surmounting the base ring 10 and supported thereby is an oil ring 19 of ring form providing a draft passage 20 upwardly through the center thereof. The draft passage 20 is of smaller diameter than the draft passage 11 in the base ring and the oil ring 19 slightly overlaps the inner edge portion of the base ring 10. The draft ring 19 is provided with a depending outwardly curved supporting flange 21 which seats in the generating cup 12 of the base ring 10 and is provided with spaced openings 22 in its lower edge to establish communication in the generating cup between the opposite sides of the supporting flange 21. This admits free passage of air and oil beneath the oil ring and over the inner edge of the base ring 10.

The oil ring 19 is U-shaped in cross section to provide a relatively deep annular trough, and fitting in this trough is an inner lining 23 of similar shape but having outward flanges 24 at its upper inner and outer

marginal edges to seat upon the upper edges of the draft ring 19. In the bottom of this draft ring 19, so formed, is placed a ring of asbestos 25 wrapped about a core of wire 26, and fitting in the draft ring above the asbestos 25 is a body of wood ashes 27 or the like which is levelled with the upper edge of the draft ring.

An oil feeding pipe 28 is carried upwardly into the draft ring 16 and through one side of the overflow pan 13, the pipe 28 being thence carried upwardly through the draft opening 11 at one side thereof and opens into the bottom of the oil ring 19. The oil ring 19 is provided in its draft opening 20 with a cross bar 29 extending across the lower edge of the draft ring and which supports a threaded stem 30 which extends upwardly through the draft opening 20 and supports a spreader cap or disk 31. The disk 31 extends in overlapping relation at its outer edge with respect to the oil ring 19 and terminates inwardly of the outer edge thereof, and completely covers the upper end of the draft opening 20 so as to spread and direct the upwardly flowing air outwardly over the upper surface of the body of wood ashes 27.

In the operation of the burner, oil enters through pipe 28 into the bottom of the oil ring 19 and is absorbed by the asbestos 25 and is broken up by contact with the wire core 26. The oil follows the wire core 26 and is evenly distributed about the bottom of the annular oil ring 19 as the oil will follow the metal more readily than the ashes. The oil, being broken up, enters the body of wood ashes 27, and when the same are heated, the oil is vaporized and such vapor is permitted to escape at the upper surface of the body of ashes 27 and is brought into contact with the air which is passing from beneath the disk 31 and over the oil ring 19.

The openings 22 in the base 21 of the oil ring 19 admit free air to pass around burner 16 when the draft is high and thus checks vibration or back pressure in the burner, this being an important feature of the present burner and effecting the automatic regulation of the draft under all kinds of weather conditions and admitting the proper amount of oxygen at all times to produce the steady blue flame.

It will be noted that the overflow pan is below the air inlet and is fireproof and is relatively large as it extends to the outer edge of the base ring 10 so as to catch all overflowing oil and prevent the oil from dripping outwardly from the burner. The overflow pan 13 is provided with a drain pipe 32 suitably located to carry off any excess oil which may accumulate in the bottom of the pan.

The provision of the draft ring 16 insures a complete draft through the burner at all times and prevents the draft being shut off

particularly when packing or the like is used about the burner in certain installations, such as in furnaces and the like as the draft ring 16 protects the draft openings 18 in the outer wall of the overflow pan 13.

The above described burner is adapted for installation and use in brooders, heaters, furnaces, boilers and wherever heat is required and a small amount of draft is available.

It is of course understood that various changes and modifications may be made in the details of construction and design of the above specifically described embodiment of this invention without departing from the spirit thereof, such changes and modifications being restricted only by the scope of the following claims.

What is claimed is:

1. An oil burner comprising a base ring, an oil ring surmounting the base ring, means for feeding oil to the bottom of the oil ring, distributing means in the bottom of the oil ring, vaporizing means in the top of the oil ring, a spreader disk arranged in slightly overlapping relation to the central portion of the oil ring, and an overflow pan secured beneath the base ring and having draft openings in the sides thereof for the admission of air for passage upwardly through said base and oil rings.

2. An oil burner comprising a base ring, an oil ring spaced above the base ring and being of less diameter than that of the base ring, a spreader disk arranged above the oil ring and overlapping the same, an overflow pan of the diameter of the base ring secured beneath the same and having draft openings in the annular wall thereof, and an outwardly and downwardly curved draft ring secured about the overflow pan for protecting said draft openings.

3. An oil burner comprising a base ring, an oil ring spaced above the base ring, means for feeding oil to the bottom of the oil ring, asbestos in the bottom of the oil ring to absorb the oil, a metal core embedded in the asbestos to distribute the oil evenly within the ring, and a body of wood ashes in the upper part of the oil ring for vaporizing the distributed oil.

4. An oil burner comprising a base ring, an oil ring having a depending apertured flange bearing upon the upper surface of the base ring, an overflow pan secured beneath the base ring and having draft openings in its outer wall, a draft ring secured to the top of the pan and extending downwardly and outwardly thereabout, a stem carried in the central portion of the oil ring and extending upwardly therethrough, a spreader disk mounted on the stem and partially overlapping the oil ring, a pipe leading upwardly through the overflow pan and the base ring and opening into the bottom of the oil ring, metallic spreading means in the

bottom of the oil ring, absorbing means encasing said metallic means, and vaporizing means in the top of the oil ring.

5. An oil burner comprising a base ring having an annular generating cup in its upper side forming inner and outer annular flanges with the inner flange of less height than the outer flange, an oil ring having an annular trough and provided with a dependent recessed flange seating in the generating

cup in spaced relation to and concentric with the inner and outer flanges of the cup for supporting the oil ring in spaced relation above the inner flange, means for feeding oil to the oil ring, means for spreading and vaporizing the oil in the oil ring, and means for feeding air upwardly through and between the base and oil rings. 15
